UNITED STATES PATENT OFFICE

WILLIAM S. MERSHON, OF LAKewood, OHIO

MAUSOLEUM

Application filed June 2, 1928. Serial No. 282,500.

This invention relates to community mausoleums and is particularly concerned with a new and improved form of construction which makes it commercially possible to utilize for such purpose, materials which have been prohibitively expensive heretofore.

Attempts have been made prior to this invention to utilize various materials, for example, slate, sandstone, limestone and other suitable natural stones or rocks in community mausoleums but such attempts have not been entirely successful, partly because the existing constructions rendered it necessary to use heavy sections of such materials to obtain the desired support, particularly for the shelves in the crypts. This extra thickness increased the cost and practically eliminated such materials from use when in competition with cheaper materials such as reinforced concrete. Another reason for the previous failures was that the cutting and fitting costs incident to the use of such materials were very high as compared with concrete which could be poured monolithically.

By my invention I have made it possible to extend the range and selection of materials to include many materials heretofore excluded from use in competition with the cheaper materials heretofore used and at the same time to decrease the former cost of construction including the elimination of much of the cutting and fitting heretofore performed for private mausoleums and receiving vaults.

In the drawings accompanying and forming a part of this application;

Figure 1 is a fragmentary front elevation of a community mausoleum embodying one form of my invention;

Figure 2 is a horizontal sectional view taken on line 2—2 of Fig. 1;

Figure 3 is a transverse sectional view taken on line 3—3 of Figure 2;

Figures 4 and 5 are respectively horizontal and vertical fragmentary sectional views showing one arrangement of mausoleum and an exterior wall therefor;

Figure 6 is an enlarged fragmentary sectional view taken on line 6—6 of Figure 2;

Figure 7 is an enlarged front elevational

view showing the means for preventing inward tipping of the crypt closers;

Figure 8 is an enlarged fragmentary top plan view of one form of cap;

Figure 9 is a perspective view of a modified cap and one form of partition saddle for use therewith;

Figure 10 shows in enlarged detail the correlation of the ledge shelf and side wall as taken on line 10—10 of Figure 2.

Referring first to Figures 1 to 5 inclusive, the mausoleum shown is supported on a suitable foundation 1 and consists of a plurality of upright walls 2 and horizontal shelves 3 forming a plurality of crypts 4, enclosed on the rear end and, if desired, on either or both sides with an exterior wall 5. The front of the mausoleum, shown herein, is of conventional form and consists of suitable crypt closers 6 which may be composed of marble, slate, or some similar material and corresponding closer rails 7 and ledges 8. Any suitable cover or roof for the mausoleum, shown herein, may be employed.

The mausoleum within the exterior walls 5 just described, is formed by a plurality of horizontal shelves 3, a plurality of side walls 2 and a plurality of partitions 9 together with closers 10 for each of the crypts 4 of the mausoleum. The outer walls 2 may rest at their bottom edge on the bottom row of horizontal shelves 3, or, if desired, directly on the supporting structure 1 after the manner shown in Figure 2 as regards the partitions 9. The rear end wall 11 of each crypt 4 is similarly supported either on the supporting base 1 or on the horizontal bottom shelf 3 and has its top surface in substantially the same plane as the top edges of the side walls 2. On the top of each partition a cap 12 of nearly the same length as the partition is disposed so as to project laterally on either side of the partition. These caps 12 carry on their top surfaces other partitions 9 substantially vertically aligned with the lower partitions 9.

Shelves 3 rest on the top edges of the rear walls 11, on the projecting portions of the caps 12 or on the top edges of the side walls 2. In the case of an interior crypt 4^a the shelf 3 is supported along its rear edge portion by 100

the rear wall 11 and has its end edge substantially flush with the outer surface of the rear wall 11, and is supported along its side edge portions by the projections of the caps 15 beyond the partition with its edge surfaces closely adjacent to the partitions 9 on the caps 12. In the case of an outer crypt 4 the end and one side of the shelf 3 will be supported as in the case of interior crypts 4 but the outer edge portion of the shelf 3 is supported on the top of the side wall 2. Other higher outer side walls 2 rest on the shelves 3 in vertical alignment with the next lower side wall 2, as is also the case with the next upper rear walls 11.

Several tiers of crypts may be built up in the manner just described for the first two horizontal tiers.

Each shelf 3 has one or more, and preferably at least two slides disposed on the upper surface thereof substantially as shown to constitute a slideway for a casket which is being placed in or removed from a crypt and on which the casket rests while in the crypt. The slides 13 are of sufficient thickness so that their upper surfaces are substantially flush with the top surface of the ledge 8 with which they cooperate and the slides 13 and shelves 3 have a combined thickness not less than the ledge so that the bottom surfaces of the ledge 8 and shelf 3 are substantially flush with each other.

Each crypt 4 has a front closer 10 which is preferably substantially rectangular and which rests on the shelf 8 or ledge forming the bottom of the crypt for which it is to serve as a closer. The size of the closer 10 is preferably slightly less than the opening formed by the top and bottom and side walls of the crypt. Suitable sealing material is placed in the space between the side, bottom and top walls of a crypt and the closer 10. This closer may have dowel pins in its lower edge to engage in corresponding holes 14 in the bottom shelf 3 or ledge 8 therebeneath for positioning the same against sliding movements and is prevented from tipping or tilting inwardly by the lateral projections of the cap which is adapted to engage the inner wall 10^a of the closer 10 at one corner of the latter as shown in Figure 7. Inasmuch as the cap 12 is of nearly the same length as the partition 9 and since it is desired that the closer 10 should have its front surface substantially flush with the front edge of the partition 9 the cap 12 is preferably cut away at its front edge or stopped short in the laterally extending portions thereof by an amount substantially equal to the thickness of the closer 10. The rear closers 11 are supported against inward tilting by engaging with the ends of the caps which are substantially flush with the inner surfaces of the closers 11.

In Figures 9 and 10 a modified cap 15 is shown in which transverse grooves 16 are cut

in the bottom surface thereof to accommodate saddles 17 which rest on the top edge of the partition 9 and have laterally extending portions 18 substantially the width of the cap 15 and depending walls 19 having bearing engagement with opposite sides of the partition 9. These saddles 17 may be made of bronze or other suitable material which does not corrode or deteriorate in the atmosphere of a crypt and they may be variously shaped. The main purpose of these saddles is to engage with the side surface of the partition 9 and thereby to prevent lateral tilting of the cap 15.

In Figures 4 and 5 is shown a convenient means of venting the crypts. The rear end walls 11 of the crypts are provided with one or more, and preferably at least two, vent openings 20 which communicate with vent passages 21 formed by the exterior wall 1 and the crypt. If desired the side and partition walls 2 and 9 may be projected beyond the rear surface of the rear end walls 11, as shown in these figures, the vent passages 21 being preferably disposed between each adjacent pair of such projecting walls 2 and 9 and the rear walls 11 of the crypt. When the shelves 3 rest on the tops of the side and rear walls of the crypt and the side walls 2 are extended rearwardly, as just described, horizontal vent passages 22 are formed. It is to be understood that the vertical passages 21 may be formed on the sides of a crypt if desired simply by extending the rear walls beyond the side walls 2.

In Figure 6 the marble closer is shown projecting at its top into a recess 8^a in the ledge 8 where it is retained by the marble slabs 7 which have dowel pins 7^a in the lower edge projecting into the ledge 8 and which at their upper edges project into recesses 8^b in ledge 8 thereabove.

In Figure 10 is shown the notching of ledge 8 to close the space between two adjacent side walls 2 in front of the shelf 3. The shelf 8 is similarly notched to receive partition 9 or if the shelf extends past one or more partitions it need only be grooved to take each partition. The shelf 8 thus cooperates with the partitions and is engageable with the opposite sides thereof in a manner to prevent lateral shifting of such partitions.

It will be noted that all of the walls of the mausoleum shown herein are relatively thin as compared with certain of the marble parts, for example, the ledges 8. My invention makes it possible to utilize such thin sections while still providing sufficient supporting strength and area even where some of the less strong materials are used. My construction is particularly well adapted to the use of slate and in the thin sections shown which are much thinner than the thinnest sections heretofore considered permissible with then existing forms of supporting constructions.

This is traceable in part to a new and improved means of supporting and strengthening the thin shelves. For example, the shelves have a bearing of considerable width all along the sides on the caps 12 and moreover, are not weakened by any rabbeting which has heretofore been used. The shelves are also strengthened as to load carrying capacity by the fillers which transfer the maximum load more or less uniformly from the center of the shelves acting as beams to the vertical walls acting as columns. The partitions 9 are prevented from lateral movement and are supported by the shelves 3 which are either in direct engagement with the sides thereof or are separated therefrom by small spaces 9^a which are filled with material which hardens and supports the partitions 9. The caps 12 are easily made and require substantially no special cutting except as is shown in Figure 8 to accommodate the front closer 10. The front closer can be cut into substantially rectangular form without notching and still be supported in upright position against inward tilting by the cap 12.

I have described my invention so that those skilled in the art may be enabled to practise the same and what I desire to secure by Letters Patent is defined in what is claimed, it being understood that the foregoing detailed description and the forms of constructions shown in the drawings have been employed wholly for the purpose of disclosing my invention and not in any sense for the purpose of limiting the same to such details.

Claims:

1. A community mausoleum including a plurality of crypts having upright walls, certain of said walls having vent openings therethrough for ventilating the interior of the crypts, and a wall forming, in cooperation with the said walls, common vent passages communicating with the vent openings of a plurality of crypts.

2. A community mausoleum including a plurality of crypts having upright walls provided with vent openings for venting the interior of the crypts and having a plurality of upright walls projecting outwardly beyond the said walls, and an exterior wall cooperating with the said projecting walls and forming therebetween common vent passages communicating with the said vent openings of a plurality of crypts.

3. In a community mausoleum, a crypt formed of flat disconnected members having plane side and edge surfaces including an upright partition, a cap on the partition having a front projection aligned with the partition, a shelf supported in part by the cap, and a closer supported in an upright position by the cap on one side of said projection.

4. In a community mausoleum, a crypt formed of flat, disconnected members having side and edge surfaces defined by planes, in-

cluding an upright partition, a cap on and projecting laterally beyond the partition, a shelf supported in part by said cap, and a closer disposed on one side of the partition and below the shelf in an upright position and being prevented from tilting inwardly by engagement with the projecting portion of the cap. 70

5. In a community mausoleum, a crypt formed of flat, disconnected members having plane side and edge surfaces including an upright partition, a cap supported by and projecting laterally beyond the partition, the laterally projecting portion of the cap being stopped short of one end of the partition by a distance substantially equal to the thickness of a closer, a shelf having one edge portion supported by the cap with its said edge disposed adjacent to the second partition and a closer engageable in an upright position with the stopped end of the cap to prevent inward tipping of the closer. 75

6. In a community mausoleum, an upright partition, a cap supported by and projecting laterally beyond the partition, a second partition supported by the cap, a shelf having one edge portion disposed on the cap adjacent to the second partition, and a saddle engaging the sides of the first said partition and the under side of the cap for preventing 80 inward tipping of the cap. 85

7. In a community mausoleum, a crypt formed of flat, disconnected members having side and edge surfaces lying in planes, including an upright partition, a cap resting 100 on and projecting laterally beyond the partition on each side thereof, a second partition resting on the cap in substantially vertical alignment with the first said partition, and shelves having their adjacent edge portions resting on the cap and disposed closely adjacent to opposite sides of the second partition. 105

8. In a community mausoleum, a crypt formed of a plurality of separate generally rectangular members having side and edge 110 surfaces disposed in planes, including a floor member, upright side and end members, a cap member on one side member, and a top supported at one edge on the cap, the said members mutually supporting each other by 115 surface to surface engagement of adjacent members.

9. In a community mausoleum, a crypt formed of flat disconnected members having side and edge surfaces lying in planes, including an upright partition, a cap resting on and projecting laterally beyond the partition on each side thereof, shelves having their adjacent edge portions resting on the cap, and a second partition supported by and in substantially vertical alignment with and disposed above the first said partition. 120

10. In a community mausoleum, a crypt formed of a plurality of separate generally rectangular members having side and edge 130

- surfaces disposed in planes, including a floor member, upright side and end members, top supporting means supported by a side member and projecting laterally beyond the side surface of the side member, and a top supported at one edge on the said means, the said members mutually supporting each other by surface to surface engagement of adjacent members.
11. In a community mausoleum, a crypt having upright side walls, a top, and a bottom, an upright closer disposed out of contact with the side walls and resting by gravity on the bottom, and means engageable with an upper corner of the closer for preventing inward tipping of the upper portion of the closer.
12. In a mausoleum, a crypt having a closer end and upright side walls provided with continuous parallel plane side surfaces at the closer end, and also having top and bottom walls, an upright closer for the crypt disposed out of contact with the side walls and resting by gravity on the bottom wall, and means projecting into the crypt beyond the said parallel plane surfaces of the side walls and engageable with the inner surface of the closer for preventing inward tipping of the top of the latter.
13. In a mausoleum, a crypt having a closer end and upright side walls, a top wall and a bottom wall, the said side and top walls being provided with continuous parallel plane side surfaces at the closer end, an upright closer for the crypt disposed out of contact with the said side and top walls and resting on the bottom wall by gravity, and means projecting into the crypt below the top wall and engageable with the inner surface of the closer for preventing inward tipping of the top of the latter.

In testimony whereof I hereunto affix my signature this 8th day of May, 1928.

WILLIAM S. MERSHON.
